UNITED STATES PATENT OFFICE.

BENJAMIN F. ROBINSON, OF NEW YORK, N. Y.

MERCHANT'S SHELF-BOX.

SPECIFICATION forming part of Letters Patent No. 268,939, dated December 12, 1882.

Application filed May 3, 1882. (No model.)

To all whom it may concern:

Be it known that I, BENJAMIN F. ROBINSON, of the city, county, and State of New York, have invented a new and Improved 5 Merchant's Shelf-Box, of which the following is a full, clear, and exact description.

My invention relates to folding boxes for exhibiting goods; and it consists in the peculiar construction and arrangement of parts, as hereinafter fully set forth.

Reference is to be had to the accompanying drawings, forming part of this specification, in which similar letters of reference indicate corresponding parts in all the figures.

Figure 1 is a perspective view of my new and improved shelf-box as it appears when folded. Fig. 2 is a perspective view of the same as it appears when open. Fig. 3 is a perspective view of the main part or body of the box with the hinged wings removed. Fig. 4 is a perspective view of one of the wings; and Figs. 5 and 6 are detailed sectional elevations, showing the hinges by which the wings are attached to the main body of the box. Fig. 7 is a plan view, showing the latches and hand-grasp.

A represents the main part or body of the box, which is formed of the end piece, b, bottom a, and the partial side walls, c c, which latter reach from the end piece, b, to about the center of the length of the bottom a. These side pieces are made triangular in form and of ornamental outline, as shown, and are adapted to hold the goods upon the bottom a. Hinged to the side edges of the bottom a are the wings D D of the box. These wings, when folded to close the box, form the main part of the sides of the box, one entire end, and the entire cover, as shown in Fig. 1. When unfolded they are adapted to swing back under the bottom a, as shown in Fig. 2, for supporting the main part A, so that the goods therein will be held in an elevated position for convenient inspection.

d d are the parts of the wings which, when the wings are closed, form the end of the box 45 opposite to the end b. c' c' are the parts of the wings which form the cover of the box, which are each about one-half the width of the bottom a, and f f are the parts of the wings which form the main side walls of the box. 50 The parts g g of the wings, when the box is closed, come outside of the end b, as shown in Fig. 1, and these parts are made triangular in

form and of ornamental outline, like the partial side wall, c c, of the main part A. The curved edges of the partial end pieces, g g, of the wings of the box are recessed, as shown at h h, and these recesses are so formed as to form the 55 detents or lips i i, with which the latches j j, which are hinged to the outside of the end piece, b, engage for locking the wings D D in 60 folded position. The latches j j may be formed of spring-wire and pivoted to the end piece, b, by the shank e of the hand-grasp, as shown in Fig. 7 of the drawings, thus adapting them to be raised by placing two fingers against their 65 under side and raising them free of the lips i i in the recesses h h of the wings D D. The hinges by which the wings D D are hinged to the edges of the bottom a are formed of the plates l l', which are secured respectively to the 70 under side of the bottom a and to the edges of the boards f of the wings D, as shown in Figs. 5 and 6, and of the intermediate plates, m, thus forming toggle-hinges, whereby the 75 said wings D may be swung under the bottom a, as shown in Figs. 1 and 6, and folded to close the box, as shown in Figs. 1 and 5. Upon the inside of the end piece, b, is secured the spring-clamp p, which serves to hold the goods placed 80 in the box at the ends thereto next to the end piece, b, and permits the easy removal of the pieces selected. In this manner it will be seen that the side pieces, c c, confine the goods in the box only at one end, that the outer ends of the pieces are left free to be raised for inspection upon both sides and turned back, one off from the other, for exhibiting the varieties. It will also be seen that the pieces selected may be removed from the box without materially disturbing the remainder, that when the box is 85 closed it protects the goods from dust, and that in this manner the goods are saved from the wear and damage incident to frequent handling, and that the annoyance and loss of selling by samples, as is now the practice, is overcome. 90

Having thus fully described my invention, I claim as new and desire to secure by Letters Patent—

1. A merchant's shelf-box for holding ham-burgs and similar goods, consisting of the body A, having partial side walls, and the inclosing side wings, D D, hinged to the bottom of the body, substantially as shown and described. 100

2. The inclosing side wings, D D, hinged to the body A in such manner that they are adapted to be swung over and close the box, and to be swung under the body A for supporting the same, as and for the purposes set forth.

3. The ends g g of the wings D D, formed with the lips i i, in combination with the latches j, pivoted to the end piece, b, substantially as described.

4. The latches j j, pivoted to the end b of the body A, under the hand-grasp k, in combination with the wings D D, having the lips i i, formed in the end pieces, g g, thereof, substantially as described.

BENJAMIN F. ROBINSON.
